CARBURETOR

John W. Fitz Gerald, Milwaukee, Wis., assignor
to Briggs & Stratton Corporation, Milwaukee,
Wis., a corporation of Delaware

Application August 13, 1934, Serial No. 739,625

3 Claims. (Cl. 261—52)

This invention relates to an automatic control of the gas mixture created by a carburetor employed in association with internal combustion engines.

5 The standard carburetor is generally equipped with an accelerator pump for the purpose of supplying additional fuel during acceleration. The plunger of the pump is attached to the throttle so that in operation, a rapid or quick opening 10 of the throttle causes an immediate discharge of the gasoline within the pump and does not supply a constant, steady continuous quantity of additional gasoline for utilization by the engine and consequently, the fuel-air mixture is not enriched 15 by this additional gasoline for a long enough period to satisfy the operating demand of the engine. Again, if the acceleration is slow, then the additional supply is not needed, and still the same amount of gasoline is fed by the pump to the carburetor.

With the foregoing difficulties in mind, it is the primary purpose of the present invention to provide automatic control of the gasoline mixture created by a carburetor, to the amount 25 needed for efficient carburetion during any stage or condition of engine operation.

It is another object of the invention to provide a simple and efficient means for increasing the fuel ratio of the gasoline mixture of a carburetor 30 upon sudden, or quick acceleration, by automatically lessening the air content thereof, as by closing the choke valve.

With the above and other objects in view which will appear as the description proceeds this invention resides in the novel construction, combination and arrangement of parts substantially as hereinafter described and more particularly defined by the appended claims, it being understood that such changes in the precise embodiment 35 of the herein disclosed invention may be made as come within the scope of the claims.

The accompanying drawing illustrates one complete example of the physical embodiment of the invention constructed according to the best mode 40 so far devised for the practical application of the principles thereof, and in which:

Figure 1 is a side elevation of a conventional carburetor illustrating the application of the present invention thereto; and

50 Figure 2 is a cross-sectional view taken on the plane of line 2—2 of Figure 1.

Referring now more particularly to the accompanying drawing, the numeral 5 indicates generally the conventional carburetor in which there 55 is a mixing chamber 6, an air intake 7 provided

with a butterfly valve 8, commonly known as a choke valve, a jet for the carburetor (not shown), and the conventional passageway above said jet having therein a throttle valve 9.

The throttle valve 9 is controlled in the conventional manner by means of an accelerator (not shown), and to afford the desired control of the choke valve 8 to effect an enriching of the mixture during rapid acceleration, the choke valve 8 is connected with the throttle control as 10 now about to be described.

Attached to the throttle valve stem 10 is a lever 11 connected to the rod 12 of a piston 13. The piston 13 operates in a cylinder 14 which is slidably positioned within a guide 15. The guide 15 as shown in Figure 2 is cast as an integral part of the carburetor. However, it is apparent that the guide 15 might be a separate unit and need only be fastened securely to the carburetor.

At the lower end of the cylinder 14 is an air 20 outlet 16 controlled by a needle valve 17. The lower wall 18 of the cylinder 14 has cast thereon a boss 19 to which is attached a link 20, the other end of which is pivoted as at 21 to a choke lever 22, which in turn is fixed to the choke valve stem 23. A torsion spring 24 coiled about the stem 23 with one end bearing against a stud 25 positioned on a boss 26 and its other end engaged in a notch 27 in the lever 22 normally holds the choke valve 30 open.

From the description thus far, it will be apparent that the piston 13 reciprocates simultaneously with any adjustment of the throttle valve. If the adjustment of the throttle valve is effected slowly, the piston merely reciprocates in its cylinder without in any wise affecting the position of the choke valve since the air displaced by the piston escapes through the air outlet 16. In the event the throttle valve is opened suddenly, a 35 consequent sudden depression of the piston 13 occurs with the cylinder 14 moving with the piston inasmuch as the air contained within the cylinder chamber cannot escape through the air outlet rapidly enough to permit the piston to move within the cylinder. As a result of such sudden acceleration, the choke valve 8 will be closed against the action of its spring 24 to a degree dependent upon the suddenness of acceleration and the adjustment of the needle valve 17. 40 and upon the closure of the choke valve, the fuel mixture is of course enriched, thus affording the proper mixture during the actual acceleration. 45

As will be readily apparent, the spring 24 will return the choke valve to its normal open position even though the throttle valve is held fully 55

open. The return of the choke valve to its open position with the consequent reduction in the richness of the mixture, however, is gradual depending upon the adjustment of the needle valve 5 17, so that a desired tapering off in the richness of the mixture follows a sudden acceleration.

From the foregoing description taken in connection with the accompanying drawing, it will readily appear to those skilled in the art to which 10 this invention appertains, that there is afforded thereby an efficient means to automatically coordinate the richness of the fuel mixture with the varying requirements of the operation of the engine.

15 What I claim as my invention is:

1. In a carburetor having a fuel supply and an air supply, a choke valve to control the air supply, a spring reacting against a fixed abutment and acting upon the choke valve to bias the same toward open position, a throttle valve to control the flow of carbureted fuel-air mixture from the carburetor, means for opening and closing the throttle valve, and a connection between the throttle valve and choke valve whereby sudden opening of the throttle valve closes the choke valve while gradual opening of the throttle valve permits the choke valve to remain in its open position, said connection including a cylinder connected with the choke valve to move directly in accordance therewith at all times and to be acted upon by the choke valve spring, and a piston connected with the throttle valve to move therewith at all times operating in said cylinder.

30 2. In a carburetor having a fuel supply and an air supply, a choke valve to control the air supply, a throttle valve to control the flow of carbureted fuel-air mixture from the carburetor, a connection between the throttle valve and the

choke valve whereby sudden opening of the throttle valve closes the choke valve while gradual opening of the throttle valve leaves the choke valve undisturbed in open position, said connection including a cylinder linked to the choke valve 5 to move in unison therewith at all times, a piston sliding in the cylinder and linked to the throttle valve, said cylinder and piston cooperating to provide a dash pot, a spring acting upon the linked choke valve and cylinder and reacting 10 against a fixed support to at all times yieldingly urge the choke valve to open position and the cylinder toward the piston, and a fixed stop abutment to limit the movement of the choke valve and the cylinder linked thereto in a position at 15 which the choke valve is open.

3. In a carburetor having an air supply and a fuel supply, a choke valve for controlling the air supply, a throttle valve to control the flow of carbureted fuel-air mixture from the carburetor, 20 a connection between the throttle valve and the choke valve whereby sudden opening of the throttle valve closes the choke valve while gradual opening of the throttle valve leaves the choke valve undisturbed in open position, said connection comprising a cylinder linked to the choke valve to move in unison therewith at all times and having an open end and a closed end with an air bleed through its closed end, a piston 25 slideable in the cylinder and linked through the open end of the cylinder to the throttle valve, a spring acting upon the linked choke valve and cylinder to yieldingly urge the same in a direction to open the choke valve, and means to constrain the 30 movement of the cylinder and limit its motion under action of said spring in a position at which the choke valve is open.

JOHN W. FITZ GERALD.
